UNITED STATES PATENT OFFICE.

WILLIAM C. MOFFATT AND ARNOLD VON SCHRENK, OF ALBANY, NEW YORK.

TRANSFER-TICKET.

1,201,605.

Specification of Letters Patent.

Patented Oct. 17, 1916.

Application filed March 3, 1913. Serial No. 751,723.

To all whom it may concern:

Be it known that we, WILLIAM C. MOFFATT and ARNOLD VON SCHRENK, both citizens of the United States, and residents of 5 Albany, county of Albany, State of New York, have invented a new and useful Improvement in Transfer-Tickets, of which the following is a specification.

Our invention relates to transfer tickets 10 of the kind particularly adapted for use on street and interurban railways for transferring passengers from one line of cars to intersecting lines and has for its object to arrange the said ticket so that the same is 15 easily readable whereby the receiving conductor may, by simply glancing at it, know whether or not the ticket is being properly or improperly used.

A further object of our invention is to 20 reduce the liability of mispunching on the part of the issuing conductor and at the same time to make said ticket more intelligent to the ordinary passenger.

Our invention also contemplates a transfer ticket which may serve as a guide to 25 passengers who are strangers and are not familiar with a given system of cars and lines and which for instance will indicate the territory being traversed and show how 30 or where combinations of rides are possible.

A still further object of our improvement is to provide a transfer ticket which will enable the issuing conductor to punch it in 35 a manner to indicate to the receiving conductor, the complete ride of the passenger holding the transfer and thus prevent said passenger from making a complete circuit of the line or any other unauthorized combination of rides for a single fare.

40 Other advantages of our improvement will appear from the description hereinafter and the features of novelty will be pointed out in the appended claims.

Reference is to be had to the accompanying 45 drawing which shows, as an example of our invention, a face view of one form of transfer ticket arranged according to our improvement.

As shown in the drawing the ticket comprises the main or body portion 1 which may be provided at one end with a portion 2 having a main column of figures indicating the twelve hours of the day and auxiliary columns of figures indicating sub-divisions 50 of said hours in any given and desired ratio;

said ticket may further be provided at its opposite end with what is commonly known as a p. m. coupon 3, this latter being attached to the body 1 by means of a weakened line 4 or in any other suitable way to 60 enable it to be easily separated from said body 1. This coupon 3 if it remains attached to the transfer ticket when issued indicates that the time punched on the portion 2 is p. m. while if the coupon 3 is detached from the transfer when issued this indicates that the hour punched on portion 2 is a. m. The portions 2 and 3 of the illustration form no part of our invention and other arrangements may be substituted to 70 meet any requirement or the same may be omitted entirely.

Our invention resides primarily in producing a map 5 or diagrammatic representation of connecting railway routes on a face 75 of the body portion 1 of the transfer ticket, which map or the like may simply show connecting routes of a traction system on which the transfer is to be used or may illustrate a complete system showing all 80 routes thereof if desired. In either case the said map or diagram 5 may have the various parts thereof marked with the names of the designated streets or avenues or may have other indications thereon to 85 designate distances between the connecting points of two routes, and in addition may be provided with characters N, E, W, S preferably placed at proper points adjacent to the intersection of the various connecting 90 routes and indicating whether the transfer is to be used in payment of a continuing trip going north, east, west or south as the case may be. Instead of having these characters N, E, W, S placed as described they 95 may be otherwise located in any manner which may be found advantageous and in any case, are intended to indicate the direction in which the continuing trip of the passenger may be legitimately taken as will 100 appear more fully hereinafter, it being understood that in some cases these characters may be omitted entirely.

In using our improved transfer, assuming a passenger to be traveling east on Washington avenue and desiring to transfer at Pearl street to a car on this latter street, the issuing conductor on the Washington avenue car will punch or otherwise mark the ticket at the point on the map indicating the in- 110

tersection of Washington avenue and Pearl street which in this case would make the said ticket good for a continuing trip on a car going in either direction on Pearl street. 5 If the characters N. E. W. S. are produced adjacent to the intersection of said streets as above described the issuing conductor would punch or otherwise mark for instance the character N at the intersection of Washington avenue and Pearl street which would 10 indicate that the transfer so punched or marked is valid only for a continuing ride going north on Pearl street thus limiting the privileges of the passenger, to a continuing ride in this direction. If the characters N. E. W. S. are otherwise placed than at the intersection of the various streets or avenues and it is desired to restrict the privileges of the passenger to a continuing 15 ride in a certain direction, the conductor may punch or otherwise mark the ticket at the intersection of the streets on the map and in addition may punch or otherwise mark the character indicating the direction 20 in which the continuing ride may be legitimately taken. It will of course be understood, if the portions 2 and 3 or their equivalents form part of the ticket, that these portions will be punched or otherwise 25 made use of in the intended manner by the conductor issuing the transfer.

It will readily be seen that the great advantage of our invention resides in its simplicity and clearness and the ease with which 30 our improved ticket can be read, which means that the receiving conductor will at a glance know whether said ticket is being used properly or improperly. When a large number of transfers are presented at once, 35 as during rush hours of travel, the receiving conductor has very little time in which to carefully examine and read each transfer presented and with existing forms consequently is bound to accept many transfers 40 which are faulty and improperly used and which should be rejected, so that with existing types an extremely large financial loss due to improperly used transfers is the result. This is entirely avoided with our invention which in addition owing to the fact 45 that the matter produced on the ticket is open and not crowded together reduces the liability of the issuing conductor to mis-punch the transfer, another source of large financial loss with existing types of transfer tickets.

Our improved ticket is also more intelligent to the passenger than existing types and is consequently more likely to be carefully 50 examined by him for this reason, so that any mistakes of the issuing conductor are likely to be discovered before the transfer ticket is presented to the receiving conductor. At the same time the said passenger, 55 if a stranger to the locality by examining

the ticket can ascertain the various combinations of rides which are legitimately permitted and can also keep track of his location by simply comparing the locality being traversed with his ticket and keeping track 70 of the indications, for instance streets, thereon for which reason said passenger is not likely to be carried beyond the point at which he wishes to leave the car.

Our improved transfer is further readily 75 checked by the department of a street railway which is usually assigned to such work and cannot only be checked very rapidly but mistakes occurring thereon are also easily detected.

Our improved transfer may also be used to show the complete ride of any passenger, the issuing conductor in this instance in addition to punching or otherwise marking the point at which the transfer is to be used, 85 also punching or otherwise marking the ticket at the point at which the transfer is issued or at a place approximating the point at which the passenger entered the car. It will readily be seen, if both the issuing 90 point and transfer point are shown, that the receiving conductor can tell at a glance whether the passenger is making a round trip or other unauthorized combination of rides and can act accordingly.

Our improved ticket after having been once issued and used may also be used for the purposes of transferring a second time; in this case the conductor first receiving the transfer, in the specific case illustrated the conductor on the Pearl street car, might punch or otherwise mark the ticket again at the point on the diagram indicating the junction of Pearl street and Clinton avenue, which would make the transfer valid 100 for a further continuing ride on Clinton avenue by the passenger first receiving it. If the characters N. E. W. S. are used the character W might be punched or otherwise marked to indicate that the continuing ride 105 on Clinton avenue is to be in a westerly direction.

Our invention has many other advantages too numerous to mention, over existing forms of transfer tickets and substantially 115 obviates the tremendous financial loss suffered by traction companies due to misuse of transfers and to faulty transfers.

It will also be apparent that the illustration is only one example of our invention and that many changes and variations may be made within the scope of the claims without departing from the spirit of our improvement.

We claim:

1. A transfer ticket having a diagrammatic representation of connecting railway routes produced on a face thereof, said diagrammatic representation being adapted to be punched or marked at predetermined 120

points, when the ticket is issued whereby the continuing trip for which said ticket may be validly used is indicated.

2. A transfer ticket having a diagrammatic representation of connecting railway routes produced on a face thereof and indications on said diagram to designate distances between connecting points, said diagram being adapted to be punched or 10 marked at predetermined points when said ticket is issued whereby the trip for which said ticket may be validly used is indicated.

3. A transfer ticket having a diagrammatic representation of connecting railway 15 routes produced on a face thereof, indications on said face in coöperative relation to said diagram and designating directions of travel, said diagram and indications being adapted to be punched or marked when 20 said ticket is issued, whereby the trip and direction of travel for which said ticket may be validly used is indicated.

4. A transfer ticket having a diagrammatic representation of connecting railway 25 routes produced on a face thereof, said diagrammatic representation being adapted to be punched or marked at the point of connection of two routes, when the ticket is issued whereby the connecting route on 30 which said ticket may be validly used is indicated.

5. A transfer ticket having a diagrammatic representation of connecting railway routes produced on a face thereof and in-

dications designating directions of travel 35 produced on the same face and located adjacent to the points of connection of two routes, said diagram and indications being in coöperative relation to said diagram adapted to be punched or marked when the 40 ticket is issued whereby the transfer point at which said ticket is to be used and the direction in which it is valid are indicated.

6. A transfer ticket having a diagrammatic representation of connecting railway 45 routes produced on a face thereof, indications forming part of said diagram designating distances between connecting points, and additional indications also forming part 50 of said diagram and designating directions of travel, said additional indications being located adjacent to said connecting points in coöperative relation to said diagram and adapted to be punched or marked, when the ticket is issued, whereby the transfer point 55 at which said ticket is to be used and the direction in which it is valid is indicated.

In testimony whereof we have hereunto set our hands in the presence of two subscribing witnesses.
